KNIFE SHARPENER

Alfred W. Madl, Milwaukee, Wis., assignor to The John Oster Manufacturing Co., Milwaukee, Wis., a corporation of Wisconsin

Application August 5, 1957, Serial No. 47,226

Term of patent 14 years

(Cl. D37—1)

FIG.1.

FIG.2.

FIG.3.

FIG.4.

Figure 1 is a perspective view of a knife sharpener, embodying my new design, viewing the same from the front, top and one side thereof;

I claim:

The ornamental design for a knife sharpener, as shown.
